(57) **CLAIM**

The ornamental design for a beverage bottle with grips, as shown and described.

DESCRIPTION

FIG. 1 is a top, front and side perspective view of an ornamental design for a beverage bottle with grips according to the present invention;

FIG. 2 is a front elevation view thereof, the rear elevation being identical thereto, except for the unclaimed threads;

FIG. 3 is a left side elevation view thereof, the right side elevation view being a mirror image thereto, except for the unclaimed threads.

FIG. 4 is a top plan view thereof; and,

FIG. 5 is a bottom plan view thereof.

All portions shown in broken lines are environmental and illustrative only and form no part of the claimed design.
